UNITED STATES PATENT OFFICE.

EDWARD SAMUEL RITCHIE, OF BROOKLINE, MASSACHUSETTS.

MARINER'S COMPASS.

SPECIFICATION forming part of Letters Patent No. 291,403, dated January 1, 1884.

Application filed September 25, 1883. (No model.)

To all whom it may concern:

Be it known that I, EDWARD SAMUEL RITCHIE, of Brookline, in the county of Norfolk, of the Commonwealth of Massachusetts, have invented a new and useful Improvement in Mariners' Compasses; and I do hereby declare the same to be described in the following specification and represented in the accompanying drawings, of which—

- 10 Figures 1 and 2 are transverse sections of compass-bowls provided with my improvement, one of them showing it as applied to the compass-glass-sustaining frame and bowl, and the other to the bottom of the bowl. Fig. 3 is a top view, and Fig. 4 a transverse section, of an expansive annulus, such as I use in carrying out my said invention. Fig. 5 is a transverse section of two of such annuli combined, as one or more of them may be used. 20 Fig. 6 is a section showing the two annuli connected together and to the bowl and the frame for sustaining the glass disk or cover.

The invention relates to what are usually termed "liquid-compasses," or those in which 25 the bowl is filled with a liquid and the compass-card is immersed therein, the object of the improvement being not only to provide compensation for unequal expansion or contraction of the bowl or liquid, induced by 30 changes of temperature, but also to prevent any injurious pressure upon the bowl or its glass pane, as well as escape of liquid from or admission of air into the bowl, such as might result by reason of such changes of temperature. To this end I combine the annular frame that supports the glass pane or cover 35 with the bowl, or the bottom of such bowl, with the body thereof by means of an elastic annulus, or by two or more elastic or yielding 40 annuli, or by an annulus made of thin plate metal and corrugated transversely. The bowl may be in one piece of metal, corrugated in its sides. This yielding or elastic annulus formed of thin plate metal, is shown in Fig. 1 at A, it being soldered at one edge or flange to the holder B, that sustains the glass pane C, and at the other to the bowl, the annulus being arranged between the said holder and bowl in manner as represented. 50 In Fig. 2 the elastic annulus A is represented as similarly applied to the body and

bottom of the bowl, the said bottom being connected to the body by such annulus, the bottom in this instance being composed of a glass disk or pane, a, and an annular sustaining-frame, b, therefor. The bottom may be constructed without any glass plate let or fixed in it. In each case there may or should extend around the connecting annulus, outwardly of it, an annular guard or protector, c; and, if desired or necessary, there may be another such guard extended from the bowl and arranged to project upward within the expansive annulus in manner as represented at c' in Fig. 1. The holder of the glass pane is to be 65 connected with the bowl by means of the expansive single or compound yielding annulus only, in order for the bowl or the holder to be free to move upward or downward, the annulus yielding to such movement, and at the 70 same time preserving a liquid-tight joint or connection between the bowl and the holder of the glass pane or disk, or between the bottom and body of the bowl, where the said bottom and body are connected by the annulus. 75

From the above it will be seen that a compass-bowl having a yielding annulus or its equivalent arranged in and applied to it in manner substantially as described can accommodate itself to the expansion or contraction of the liquid within it, or the metal of such body, so as to always remain full of such liquid, and this without danger to the glass disk or pane, or any other part of the bowl, being injured or cracked by any such change, 85 due to any increase or decrease of atmospheric temperature or from other cause. 80

The yielding annulus, as shown in Figs. 3 and 4, is a thin flat ring having flanges at its edges, as represented. The ring may be perfectly flat, or it may be somewhat conical or inclined transversely. 90

The compass described in the United States Patent No. 14,251 is not a "liquid-compass," or one in which the card is surrounded by a liquid contained in the bowl, but is an ordinary mariner's compass having no liquid in its bowl, and having to such bowl a dome-shaped cover of glass, within which is a ring of metal, to fit upon or around the bowl, and 95 around the said ring and between it and the glass cover is a ring of india-rubber. Thus 100

it will be seen that to such a compass there was no glass-pane holder, nor any connection of such to the body of the bowl by a yielding annulus of any kind, especially such as hereinbefore described.

I claim—

1. In a liquid-compass, the body of the bowl combined with the bottom thereof, or with the glass-pane holder, by means of a yielding annulus, or by two or more yielding annuli, substantially and arranged and applied as set forth.

2. The body of the bowl not only combined with the bottom thereof, or with the glass-pane holder, by means of a yielding annulus, or by two or more yielding annuli, arranged and adapted as described, but provided with one or more guards, as represented, arranged with the yielding annulus or annuli, and for the protection thereof, as set forth.

EDWARD SAMUEL RITCHIE.
